SAFETY WARNING LAMP

Roy Basil Walter Lowndes, 79 Hollie Lucas Road,
Kings Heath, England

Filed Dec. 11, 1974, Ser. No. 531,764

Claims priority, application Great Britain June 15, 1974

Term of patent 14 years

Int. Cl. D10—06; D26—02

U.S. Cl. D10—114

Fig. 3.

Fig. 4.

Fig. 5.

FIG. 1 is a perspective view of a safety warning lamp showing my new design;

FIG. 2 is an end elevation of the lamp in FIG. 1 taken from the right hand side;

FIG. 3 is a top plan view of the lamp in FIG. 1; and FIG. 4 is a bottom plan view of the lamp in FIG. 1; and FIG. 5 is a rear elevation of the lamp in FIG. 1.

I claim:

The ornamental design for a safety warning lamp, as shown.
